(57) **CLAIM**

I claim the ornamental design for a shopping cart handle cover, as shown and described.

DESCRIPTION

FIG. 1 is a perspective view of a shopping cart handle cover showing my new design as assembled.

FIG. 2 is a front elevation view thereof.

FIG. 3 is a rear elevation view thereof.

FIG. 4 is a left-side elevation view thereof.

FIG. 5 is a right-side elevation view thereof.

FIG. 6 is a top plan view thereof.

FIG. 7 is a bottom plan view thereof.

FIG. 8 is a perspective view of the claimed design as unassembled and flattened.

FIG. 9 is a rear elevation view thereof.

FIG. 10 is a front elevation view thereof.

FIG. 11 is a left-side elevation view thereof.

FIG. 12 is a right-side elevation view thereof.

FIG. 13 is a top plan view thereof.

FIG. 14 is a bottom plan view thereof.

FIG. 15 is a perspective view of the claimed design as assembled on a shopping cart; and,

FIG. 16 is a detail view thereof taken from detail 16 of FIG. 15.

The broken lines are to show portions of the shopping cart handle cover and form no part of the claimed design. The shopping cart shown in broken lines in FIGS. 15 and 16 are to show environment and form no part of the claimed design. The shopping cart handle cover is shown with a symbolic break in its length. The appearance of any portion of the cover between that break lines form no part of the claimed design.
